[57] **ABSTRACT**

A display device having a plurality of relatively movable support members provided with cooperable merchandise-receiving and display spindle elements. A holder is provided for being held on the spindle elements, one of the spindle elements having means for holding the holder in an open hanging position so that the holder need not be completely removed from the device when it is desired to remove the article.

THEFT-PROOF MERCHANDISE DISPLAY HAVING A HANGING-TYPE HOLDER

BACKGROUND OF THE INVENTION

The invention pertains generally to a display device having relatively movable support members provided with opposed and cooperating spindles, and a holder is provided for being attached to the spindles.

A display device of the general character to which the invention relates is shown in the U.S. Pat. No. 3,517,827, issued June 30, 1970 and entitled "Theft-Proof Merchandising Display." Furthermore, the improved holder provided by the present invention is in the nature of an improvement over the holder shown in the U.S. Pat. application Ser. No. 56,507, filed July 20, 1970 which issued on May 9, 1972 U.S. Pat. No. 3,661,273, and entitled "Theft-Proof Merchandise Display Having Holding Adaptor." In the holder shown in said patent, all three sections of the U-shaped holder were hinged relative to one another, but it was awkward to remove the article and also to again replace another article in the holder for reassembly in the display device.

SUMMARY OF THE INVENTION

The present invention provides a display device having oppositely disposed support members with spindles extending therefrom, the upper spindle of which has means for permitting a holder to hang loosely from the device while the article is being removed from or replaced therein. In this manner, the holder can be retained in a hanging position on the device so that it need not be handled separately and become misplaced or lost, and this further facilitates again inserting a new article in the holder for support by the display device. The invention also provides an improved holder which is generally of a U-shaped construction and having a lower leg, a side member and an upper leg, the lower leg and side member of which are rigidly secured together while the upper member is hinged on the side member; this construction provides a support for the article and prevents its falling from the holder even though the holder may be partially open at its hinged joint.

These and other objects and advantages of the invention will appear hereinafter as this disclosure progresses, reference being had to the accompanying drawings.

BRIEF DESCRIPTION OF THE DRAWINGS

FIG. 1 is a perspective view of a display device and showing the adaptor when holding the article to be displayed, locked in the device;

FIG. 2 is a fragmentary, vertical sectional view of a portion of the device of FIG. 1, on an enlarged scale;

FIG. 3 is a fragmentary view similar to FIG. 1 but with the support member in open position, and with the adaptor open to permit removal of the article;

FIG. 4 is an enlarged elevational view of the upper spindle and showing the anvil by means of which it is fastened to the upper support member;

FIG. 5 is an enlarged sectional view of a spindle attached to the upper support member and showing a portion of the holder hanging therefrom, certain parts being shown as broken away or removed for clarity.

FIG. 6 is a side elevational view of the improved holder;

FIG. 7 is an elevational view taken along line 7-7 in FIG. 6;

FIG. 8 is an elevational view taken along line 8-8 of FIG. 6; and

FIG. 9 is a vertical sectional view of the holder taken generally along the line 9-9 in FIG. 7 but a certain portion of the side of the holder being shown as broken away.

DESCRIPTION OF THE PREFERRED EMBODIMENT

A merchandise display shown herein as usable with the invention comprises a pair of axially-spaced supports 12 and 14 which are of disc shape and each having a central aperture for rotation on an upright shaft 16 which is secured to and extends upwardly from a suitable base 18.

Supports 12 and 14 are preferably rotatably received on the shaft 16 and, for this purpose, suitable anti-friction bearings 20 and 22 may be provided below the lower member 12 and above the upper member 14 of each pair respectively. Each pair of supports 12 and 14 are also spaced axially from each other a minimum predetermined distance while being relatively axially movable to a limited extent beyond such predetermined minimum. For this purpose as well as to key the supports 12 and 14 of each set together and thereby prevent relative rotational movement thereof, the support 12 is provided with an annular series of spaced upwardly-directed spacer and guide posts 24 each having a reduced end portion 26 slideably received in an aligned aperture 28 in the other support 14, and the support 14 is formed with a similar annular series of alternately-spaced downwardly-directed spacer and guide posts 30 each also having a reduced end portion 32 slideably received in an aligned aperture 34 in the support 12.

Axial displacement of the supports 12, 14 is prevented by means of pins 36, 38 or the like adjacent the ends of the reduced portions 26, 32 of the respective posts 24, 30, and these pins 36, 38 cooperate with the shoulders 40, 42 formed by the respective reduced portions to permit limited relative axial movement of the supports 12, 14 within predetermined limits. The supports 12, 14 are furthermore constantly resiliently urged apart by means of a spring 44 or the like to the fullest extent permitted by the stops 36, 38, the coil spring 44 being compressed between the adjacent faces of the supports 12, 14.

Each of the supports 12, 14 is formed with an annular series of equally spaced axially aligned spindle shafts 46, 48 respectively for receiving articles 72 to be displayed. As shown, the spindle shafts 46 project upwardly from the lower support 12 toward the downwardly projecting spindle shafts 48 of the upper support 14 of each set.

A holder H of generally U-shaped construction and having a lower member 49, a side member 50 and an upper member 51 is provided for being held by the pairs of opposed upper and lower spindles, as will more fully appear.

To simultaneously lock the holder H against displacement from the spindle shafts 46, 48, it is only

necessary to move the supports 12, 14 axially toward each other to the extent permitted by the shoulders 40, 42 of the reduced portions 26, 32 of the guide posts, and for such purpose, a cam lever 52 is provided on the shaft 16 above the upper support 14. This cam lever 52 may be pivotally secured to the shaft 16 as by means of a pivot pin 54 and has a cam surface 56 coaxing with the upper bearing 22 to further compress the spring 44 and move the supports 12, 14 axially toward each other when swung to one position while permitting the spring 44 to spread the supports 12, 14 apart when swung to an open position.

It will be noted that the upper spindle 48 has a reduced intermediate portion 60. As shown in FIG. 4, the spindle is attached to the upper support by the expediency of providing an anvil 61 snugly against the shoulder 62 and then driving the spindle downwardly so as to cause portion 62 to flare, as shown in FIG. 5, thereby securely fixing the spindle in the upper support 14. It will be noted that the spindle also has a lower shoulder 63 which, as shown in FIG. 5, is adapted to receive the holder H and permit it to be hangingly suspended from the spindle when the holder is in the open position shown in FIG. 3. For this purpose, the upper member 51 of the holder has an aperture 65 which is of tapered construction and which is of such size that it very snugly slides over the lower portion 66 of the spindle, but when in the hanging position, the holder will not slip off the spindle but instead is retained against the shoulder 63.

The improved holder H provided by the present invention has its lower member 49 and its side member 50 formed as an integral L-shaped part, while the upper member 51 is hinged to the side member by means of the hinge pin 67. The lower member also has an opening 68 which is in alignment with upper opening 65. A pair of inwardly-turned flanges 69 and 70 are provided, respectively, on the inner ends of upper member 51 and lower member 49 so as to retain the article 72, such as a tape cassette, securely in the holder. The holder also has opposite flanges 74 and 75 extending around each of the members 49, 50 and 51, thereby holding the article 72 captive in the assembled holder.

The holder H itself is preferably formed from high-impact styrene, for example, of the type made by Dow Chemical Company.

When it is desired to remove an article from the locked position shown in FIG. 1, the upper support 14 is raised, as shown in FIG. 3, and the holder lifted slightly to cause the lower member 49 to be free of its spindle 46. The holder can then be pivoted about its hinge to the open position shown in FIG. 3, while at the same time, the upper member 51 is still attached to the upper spindle 48. In this manner, the article 72 can be removed from the hanging holder without the operator having to pay any attention to the holder itself. This can be more or less of a one-handed operation and it is also an easy matter to reassemble another article in the holder for replacement in the display device. By having

the lower member 49 and side member 50 made in one piece, the holder, as shown in the position of FIG. 3, can still support the article 72 to some extent, thereby minimizing the danger of the article inadvertently falling. In this position, the flange 70 and the side flanges 74 and 75 act to support the article.

I claim:

1. In a combination with a display device of the type having a pair of oppositely disposed supports, said supports each having projecting spindles which are in axial and opposed vertical alignment, the upper spindle having an annular groove around its periphery which defines a shoulder on said spindle, one of said supports being shiftable relative to the other support for varying the distance therebetween, a holder between said opposed and aligned spindles, said holder having a lower member, a side member and an upper member, said upper and side members being foldable relative to one another and said lower and side members being rigidly fixed together, said members defining a generally U-shaped holder having an open inner side and which holder can embrace the article to be displayed, said upper and lower member having free ends adjacent said open side and an aperture adjacent said free ends for receiving said spindles, the aperture in said upper member being of a size that it snugly slides over said upper spindle whereby when the upper member aperture is in said groove then said upper member abuts against said shoulder and said holder can hang on said upper spindle, said holder also having flange means for embracing the article to be displayed on both sides thereof when said holder is folded into a generally U-shape to embrace said article.

2. In a combination with a display device of the type having an upper support and a lower support, said supports each having projecting spindles which are in axial and opposed alignment, the spindles of said upper support having an annular groove therearound defining an annular shoulder at the lower end of said groove, one of said supports being shiftable relative to the other support for varying the distance therebetween, a holder between said opposed and aligned spindles, said holder having a lower member, a side member and an upper member, said upper and side members being foldable relative to one another between holder open and holder closed positions, said lower and side members being rigidly fixed together, said members defining a generally U-shaped holder which can embrace the article to be displayed, said upper and lower members having free ends and an aperture adjacent said free ends for receiving said spindles, the aperture of said upper member being located in said groove and having a diameter such as to snugly slide on said upper spindle so as to cause said holder to abut against said shoulder and hang from its upper spindle when said holder is in said open position, said holder also having flange means for embracing the article to be displayed on both sides thereof when said holder is folded into said closed position in a generally U-shape to embrace said article.
